UNITED STATES PATENT OFFICE

FRANK A. MAGEE, OF CHICAGO, ILLINOIS, ASSIGNOR TO TRAV-LER MANUFACTURING CORPORATION, OF CHICAGO, ILLINOIS, A CORPORATION OF ILLINOIS

RADIO RECEIVING DEVICE

Application filed July 21, 1927. Serial No. 207,456.

My invention relates to portable radio receiving apparatus and has for its principal object the provision of an antenna for the receiving apparatus which may be easily set up in operative position on the container for the apparatus or packed away with the apparatus in the container for carrying it from place to place.

It is also a purpose of this invention to provide a portable radio receiving apparatus with a loop antenna structure which is adapted for use either as a loop antenna or in conjunction with the set and a large outside antenna as a transformer having the primary connected in the outside antenna circuit and a secondary connected to the receiving apparatus.

Other objects and advantages of the invention will appear as the description proceeds when taken in connection with the accompanying drawings wherein the preferred form of the invention is disclosed. However, I wish it to be distinctly understood that I do not intend to limit myself to the exact details shown and described, but that I intend to avail myself of all such modifications as would occur to one skilled in this art and as fall within the scope of the claims.

In the drawings:

30 Fig. 1 is a front view showing my improved antenna set up in operative position with respect to the portable receiving apparatus in conjunction with an outside antenna;

35 Fig. 2 is a section on the line 2—2 of Fig. 1; and

40 Fig. 3 is a plan view showing the combined loop antenna and transformer mounted in the cover on the portable container housing the receiving apparatus.

Referring now in detail to the drawings, the numeral 5 represents a container having therein a portable radio receiving apparatus such as that shown in my co-pending application Serial No. 151,773, filed November 30, 1926, for portable radio receiving sets. This container as shown is provided with a handle 6 on top thereof and in the front face the opening 7, through which the sound waves emanate from the set, and in

the lower portion of the front face is provided with a tuning dial shown at 8 and the connecting posts 10 and 11.

This front face is provided also with a false cover 12 shown in Fig. 1 in open position, which cover as shown in Fig. 3 is adapted to receive and detachably retain the frame member 13 therein. This frame member, which may be constructed of any suitable material, is provided at one end portion thereof with the hinge member 14 having the depending pin 15 thereon fitting in an opening 16 provided in a mounting member 17 on top of the container 5. The hinge member 14, as shown clearly in Fig. 2, is adapted, when it is desired to store the frame within the cover 12, to swing upwardly within the confines of the frame member and in this position forms a handle whereby the frame member may be lifted out of the cover.

The frame member 13, as shown, is provided with an external groove extending around the outer surface thereof and in this groove there are wound the primary coil 20 consisting of a small number of turns of insulated wire held out of engagement with the bottom of the groove by means of the insulating spacing members 21 provided at each angle in the frame member. This primary coil has one end secured to the binding post 22 and the other end thereof secured to the binding post 23 which binding posts may be connected by suitable leads shown at 24 and 25 to an aerial 26 and ground 27. Also wound in the groove in the member 13 are relatively large number of turns of a secondary coil 28 which is spaced from the primary coil 20 by means of the spacing members 29 mounted at the corners of the frame 13. This secondary, as shown in Fig. 1, has a pair of leads 30 and 31 connected to the opposite ends thereof and adapted to be attached to the terminals 10 and 11 on the front face of the portable container 5. Thus, as shown at Fig. 1, the frame member 13 supports the coils 20 and 28 forming primary and secondary coils of a transformer for transmitting energy from the antenna 26 to the receiving apparatus within the container 5.

106

Now when it is desired to use only the loop antenna, no connections are made at the binding posts 22 and 23, and the secondary coil 28 is utilized as a loop antenna for the interception of radio waves and their transmission to the receiving apparatus housed within the container 5. The frame 13, therefore, with its primary and secondary coils 20 and 28 is very readily adaptable for use either as an antenna or as a transformer in connection with a separate antenna when desired.

This construction also has the advantage that it can be readily dismounted and fitted within the cover 12 for transportation purpose, the cover 12 serving to protect the adjusting dials on the face of the container 5 and at the same time to carry the antenna structure.

It is thought that the above description will make the construction and advantages of this invention apparent to those skilled in this art, and having thus described my invention what I claim and desire to secure by Letters Patent of the United States is:

1. A combined transformer and loop antenna comprising a rigid supporting frame, a primary coil wound thereon and having terminals for connection to an antenna and ground, a secondary coil forming a loop antenna wound on said frame and having connecting leads for connection to a receiving apparatus, and a support member hinged to said frame and movable from a position within the outline of said frame to supporting position exteriorly of said frame.

2. A loop antenna comprising a rigid frame forming a closed loop, said frame having means in the outer surface thereof supporting a wire coil and a support member for mounting said frame secured thereon and movable from a position within the outline and plane of said frame to an opposite position exteriorly of said frame for supporting said frame.

In witness whereof, I hereunto subscribe my name this 13th day of July, A. D. 1927.

FRANK A. MAGEE.
